UNITED STATES PATENT OFFICE.

MAUNSELL B. JACKSON, OF TORONTO, ONTARIO, CANADA.

STARTER FOR ENGINES.

Application filed July 8, 1925. Serial No. 42,324.

This invention relates to starters for internal combustion engines, and more particularly to that type in which a starter pinion is threaded on a starter shaft for axial movement thereof. Heretofore it has been the general practice to form a short or small pitched thread on the starter shaft whereby the force tending to move the pinion axially of the shaft is greater than the force tending 5 to move the pinion rotarily on the shaft so that the pinion is easily moved, due to inertia, along the shaft into mesh with a gear on the engine. This short pitch had a disadvantage in that when the teeth of the 10 pinion and the teeth of the engine gear met end to end, the axial force being greater than the rotary force, the pinion often did not turn and an axial jam resulted which damaged the teeth on both gear and pinion. 15 To remedy this axial jam a yielding flexible drive was devised whereby the pinion was not driven directly from the starting motor shaft but was usually threaded on a loose sleeve which was in turn driven from the 20 motor shaft by a spring or some such device. This made the axial jamming less frequent though it did not eliminate it entirely but it had the disadvantage of necessitating the turning down of the shaft and consequent weakening of it just where strength 25 was most wanted. The yielding flexible drive construction is expensive to manufacture and assemble and very liable to get out of order.

30 Long pitched threads on the starter shaft have been used to overcome the above objectionable features but, with this type of thread, the pinion has a tendency to slide along the shaft, due to road jars or on going down a steep grade, and mesh or contact with the engine gear when the latter is running. The objects of the present invention are to overcome the objectionable features of 35 both types of starter and to provide a simple starter which may be cheaply manufactured and yet be durable and efficient.

I attain my object by means of the constructions hereinafter described and illustrated in the accompanying drawings in 40 which—

45 Fig. 1 is a side elevation of the starter shaft, the starter motor casing being partly shown in section;

Fig. 2 a side elevation of the shaft showing the pinion in its inoperative position; 55

Fig. 3 a similar view showing the pinion in its operative position;

Fig. 4 an end elevation of Fig. 3; and

Fig. 5 a section of the starter pinion.

In the drawing like reference numerals 60 indicate corresponding parts in the different figures.

B is an extended armature shaft of an electric motor G (only partly shown). This shaft is provided with a long pitched 65 double or triple thread on which a pinion A is screw threaded. On the end of the shaft remote from the motor is slidably mounted a sleeve C which is counterbored to provide clearance for the threads on the 70 shaft B and to form a shoulder c¹ adapted to engage the ends of the threads to limit the axial movement of the sleeve in one direction. A casing H is provided with an opening adapted to receive the turned down 75 threaded end b⁴ of the shaft B and a nut is threaded on this end to secure the casing on the shaft. The casing has a telescopic fit on the sleeve C to exclude dust and dirt from the interior of the former in which a 80 spring D is carried. This spring is disposed on the shaft B and engages the end of the casing and the sleeve to tend to position the shoulder c¹ in engagement with the ends of the threads on the shaft B. 85

The pinion A is adapted to be meshed, by means of the spring D as hereinafter described, with a gear E connected with the crank shaft of an engine (not shown), the common practice being to secure the gear 90 to the engine flywheel. The entering ends of the pinion teeth are tapered off as shown to facilitate the meshing of these teeth with the teeth of the flywheel gear, it is adapted to engage the resilient fingers f formed on a 95 disk F which butts against a shoulder b⁵ on the starter shaft B. These fingers limit the axial movement of the pinion, see Fig. 3, to form a rotary drive connection between the pinion and shaft whereby the flywheel 100 gear will be rotated to start the engine.

The pinion is returned to its inoperative position, when the engine is started, in the following manner. The speed of the flywheel gear when operated by the starter 105 motor is less than its speed when the engine

is started so that the instant the engine starts, the speed of the starter pinion, relative to the starter shaft, is increased. This causes the pinion to be threaded on the shaft 5 to move it out of mesh with the gear.

To prevent the pinion from accidentally sliding along the shaft, due to road jars or when travelling down inclines, and meshing with or contacting against the side of the gear E I releasably retain the pinion in its 10 inoperative position by the following means. The thread or threads on the shaft B are reduced in width, adjacent the sleeve C, to form shoulders h adapted to engage the 15 ends h^1 of the pinion threads. As the pinion is being rotated and axially moved along the shaft B, away from the gear E, it engages the sleeve C and compresses the spring D. When the ends h^1 of the pinion thread 20 pass the shoulders h on the shaft thread the pinion revolves on the shaft to bring the ends h^1 in axial alinement with the shoulders h and the spring D tends to hold the ends h^1 in engagement with the shoulders h . 25 In other words the threads on shaft B are cut away as indicated at b and b^1 and the edges a^2 and a^3 of the threads on the pinion are in engagement with the edges b^2 and b^3 of the shaft B when the pinion is being 30 axially moved on the shaft. When the ends h^1 pass the shoulders h the edges a and a^1 of the pinion teeth revolve relative to the shaft teeth and contact with the edges b and b^1 . The edges a^2 and a^3 are thus drawn 35 away from the edges b^2 and b^3 as shown in Fig. 2.

When the motor G is again energized to start the engine the shaft B rotates relative to the pinion, due to the inertia of the latter, which disengages the ends h^1 of the pinion from the shoulders h and permits the spring D to axially move the pinion to mesh with the gear. If the teeth of the pinion and gear meet end to end the former 40 is slightly rotated on the shaft until they are in position for meshing which is accomplished by the spring. This arrangement of using a long pitched thread and a spring prevents any jamming of the ends of the 45 pinion and gear teeth which would occur if a short pitched thread, adapted to axially move the pinion solely by inertia, was used. When the pinion teeth have started to mesh 50 with the flywheel teeth the shoulder c^1 engages the ends of the teeth on the shaft and limits the axial movement of the sleeve. The gear E tends to prevent rotation of the 55 pinion so that the shaft is threaded through the pinion to fully mesh the latter with the 60 gear.

What I claim is:

1. In a starter for use with an internal combustion engine having a gear adapted to rotate the crank shaft thereof, the combination of starter mechanism including a

shaft having a thread formed thereon; a starter pinion threaded on the shaft adapted to be axially moved into and out of mesh with the said gear and adapted to form a rotary drive connection with the shaft when 70 the pinion is fully meshed with the gear; and a shoulder formed in the thread of the shaft for engaging the end of the pinion thread to normally position the pinion out of engagement with the gear. 75

2. In a starter for use with an internal combustion engine having a gear adapted to rotate the crank shaft thereof, the combination of starter mechanism including a shaft having a thread formed thereon; a starter pinion threaded on the shaft adapted to be 80 axially moved into and out of mesh with the said gear and adapted to form a rotary drive connection with the shaft when the pinion is fully meshed with the gear; a shoulder formed in the thread of the shaft 85 for engaging the end of the pinion thread to normally position the pinion out of engagement with the gear; and spring means tending to maintain the pinion in engagement with the shoulder.

3. In a starter for use with an internal combustion engine having a gear adapted to rotate the crank shaft thereof, the combination of starter mechanism including a shaft 90 having a long pitched thread formed thereon; a starter pinion threaded on the starter shaft and adapted to be meshed with and drive the said gear to start the engine; a shoulder formed in the shaft thread, the 95 gear being adapted, when the engine is started, to rotate the pinion relative to the shaft and move it axially thereof to engage the shoulder; and spring means tending to maintain the pinion in engagement with the 100 shoulder, the spring also being adapted to axially move the pinion into mesh with the gear when the pinion is disengaged from the shoulder. 105

4. In a starter for use with an internal 110 combustion engine having a gear adapted to rotate the crank shaft thereof, the combination of starter mechanism including a shaft having a long pitched thread formed thereon; a starter pinion threaded on the starter 115 shaft and adapted to be meshed with and drive the said gear to start the engine, the shaft thread being reduced in width to form a shoulder, the gear being adapted, when the engine is started, to rotate the pinion relative to the shaft and move it axially thereof to engage the reduced thread on the shaft; and a spring tending to axially move the 120 pinion towards the gear to cause the end of the pinion thread to engage the shoulder. 125

5. In a starter for use with an internal combustion engine having a gear adapted to rotate the crank shaft thereof, the combination of starter mechanism including a shaft having a long pitched thread formed there- 130

on; a starter pinion threaded on the starter shaft and adapted to be meshed with and drive the said gear to start the engine, the shaft thread being reduced in width to form a shoulder; a sleeve slidably mounted on the shaft and counterbored to clear the thread thereof and form a shoulder adapted to engage the end of the thread to limit the axial movement of the sleeve in one direction; a casing secured to the shaft and having a

telescopic connection with the sleeve; and a spring disposed on the shaft engaging the casing and the sleeve, the gear being adapted, when the engine is started, to rotate the pinion relative to the shaft and move it axially thereof to engage the sleeve and the shoulder on the shaft. 15

Signed at Toronto, Canada, this 8th day of June, 1925.
